Primary Examiner — Robert M Spear*Assistant Examiner* — Marissa J Cash(74) *Attorney, Agent, or Firm* — Christie, Parker & Hale, LLP(57) **CLAIM**

The ornamental design for a transparent flowerpot, as shown and described.

DESCRIPTION

FIG. 1 is a front perspective view of the transparent flowerpot; FIG. 2 is a front elevation view thereof; FIG. 3 is a rear elevation view thereof; FIG. 4 is a left side elevation view thereof; FIG. 5 is a right side elevation view thereof; FIG. 6 is a top plan view thereof; FIG. 7 is a bottom plan view thereof; and, FIG. 8 is an exemplary diagram of the use of the transparent flowerpot thereof in which an image is displayed on a portion of the transparent flowerpot and a flower is planted in the transparent flowerpot, shown from a different perspective than FIG. 1.

The broken lines in the drawings are for illustrative purpose only and form no part of the claimed design.
